UNITED STATES PATENT OFFICE

CHARLES A. ZIERAETH, OF CHICAGO, ILLINOIS, ASSIGNOR TO THE BELL & HOWELL COMPANY, OF CHICAGO, ILLINOIS, A CORPORATION OF ILLINOIS

HUMIDOR

Application filed August 12, 1929. Serial No. 385,428.

My invention relates particularly to humidor containers for the storage of motion picture film although not limited to this use alone.

5 The object of my invention resides in the provision of a humidor wherein the moisture condition of the humidifying element of the humidor can be easily determined with a view toward maintaining a proper moisture 10 condition in the humidor, and particularly with a view toward the simple and effective incorporation of my invention in the conventional type of motion picture film humidor cans.

15 The invention will be better understood by reference to the accompanying drawings in which—

Figure 1 is a top plan view of a motion picture film can containing a reel of motion picture film and having parts broken away;

20 Figure 2 is an enlarged partial section on the line 2—2 of Figure 1;

Figure 3 is a top plan view of the humidifying and indicating elements, hereinafter described, with the humidifying element dry; and

25 Figure 4 is a similar view of the humidifying and indicating elements with the humidifying element wet.

30 Like characters of reference indicate like parts in the several views.

Referring to the drawings, 1 designates the body of the humidor which is of circular cup shaped formation, and 2 designates a similarly shaped cover engaging over the body to complete the enclosure of the humidor in a usual manner. See Figure 1. The closure so formed is adapted to contain a reel 3 having motion picture film 4 wound thereon.

35 Arranged centrally on the inside face of the transverse wall of the body 1 is a humidifying element 5, formed of blotting paper or similar material, and a foraminous plate 6 overlies this humidifying element and is secured with the body by means of tabs 7 struck from the metal of the body to secure the humidifying element with the body. See Figures 1 and 2.

40 Humidification of the enclosure is effected

by saturating the element 5 with water which evaporates therefrom.

The element 5 has different appearances when wet or dry and is preferably colored, say blue as indicated, and when dry is of 55 a lighter shade, as shown in Figure 3, than when wet or saturated as shown in Figures 1 and 4.

Interposed between the element 5 and the plate 6 is a centrally disposed relatively small indicating disk 8 of metal which is painted the same color as that of the element 5 and which has an unchanging shade corresponding with or substantially the same as that of the element 5 when it is dry and consequently lighter than or in contrast with that of the element 5 when this element is wet or saturated.

Thus the moisture condition of the element 5 may be readily determined.

While I have herein shown and particularly described the preferred embodiment of my invention I do not wish to be limited to the precise details of construction shown as changes may readily be made without departing from the spirit of my invention, but

Having thus described my invention, I claim as new and desire to secure by Letters Patent the following:

1. In a humidor the combination with an 80 absorbent humidifying element having different appearances when wet or dry, of an indicating element adapted to indicate by comparison of its appearance with that of said humidifying element the moisture condition of said humidifying element.

2. In a humidor the combination with an absorbent humidifying element having different appearances when wet or dry, of an 85 indicating element having an unchanging appearance adapted to indicate by comparison of its appearance with that of said humidifying element the moisture condition of said humidifying element.

3. In a humidor the combination with an 90 absorbent colored humidifying element having different shades when wet or dry, of an indicating element having the same color and an unchanging shade adapted to indicate by a comparison of its shade with that of said 100

humidifying element the moisture condition of said humidifying element.

4. In a humidor the combination with an absorbent colored humidifying element having different shades when wet or dry, of an indicating element having the same color and an unchanging shade the same as the humidifying element when in one of said moisture conditions thereof adapted to indicate by a comparison of its shade with that of said humidifying element the moisture condition of said humidifying element.
5. In a humidor the combination with a closure wall, of an absorbent humidifying element arranged on said wall, a foraminous plate overlying said humidifying element and secured with said wall to secure said humidifying element thereon, and a relatively small indicating element interposed between said humidifying element and said plate and adapted to indicate by comparison of its appearance with that of said humidifying element the moisture condition of said humidifying element.
6. In a humidor the combination with a closure wall, of an absorbent colored humidifying element arranged on said wall and having different shades when wet or dry, a foraminous plate overlying said humidifying element and secured with said wall to secure said humidifying element thereon, and a relatively small indicating element interposed between said humidifying element and said plate and having the same color and an unchanging shade the same as the humidifying element when in one of said moisture conditions thereof adapted to indicate by a comparison of its shade with that of said humidifying element the moisture condition of said humidifying element.

In witness whereof I hereunto affix my signature this 2nd day of August, 1929.

C. A. ZIEBARTH.
